TURNSTILE

Herbert B. Odell, Toronto, Ontario, Canada

Application March 4, 1937, Serial No. 129,000
In Canada March 10, 1936

8 Claims. (Cl. 39—3)

This invention relates to turnstiles used for controlling gateways or passages of various kinds. These turnstiles are usually mounted upon a vertical axis and have the objection that as much 5 space is occupied by the "returning" side of the rotating barrier as is occupied by the "passage" side. A further objection to turnstiles as at present constructed is that users have a habit of pushing the barrier arm part way and then passing 10 around the end of the arm, and thus leaving the arm in the midway position.

Briefly then my objects are to devise a turnstile which will require a reduced space for operation and which will be provided with centering 15 apparatus, which will come into action before the barrier has travelled half of the movement between positions and cause the movement to be completed independently of any help from the person passing the turnstile. A further object is 20 to provide a turnstile with means for positively stopping the barrier at the completion of each turn, but which, after stopping the barrier, will instantly be automatically released to permit the following person to pass the turnstile.

25 I attain my objects by means of the construction hereinafter described and illustrated in the accompanying drawing in which

Fig. 1 is a side elevation of the turnstile, the housing being shown in the section;

30 Fig. 2 a front view of the same;

Fig. 3 a top plan view of the control mechanism;

Fig. 4 a section on the line 4—4 in Fig. 3.

In the drawing like numerals of reference 35 indicate corresponding parts in the different figures.

The turnstile about to be described is intended particularly for one-way traffic.

The turnstile is mounted on a suitable standard 40 or pedestal, which in the present case is shown as a housing 1 on the rear wall of which a bracket 8 is secured.

45 Formed in this bracket is a bearing preferably of ball or other anti-friction type, for the spindle 3 of the rotating barrier. The axis of the spindle, instead of being vertical, is inclined at approximately 45° and carries on its lower end the armed barrier. This barrier is formed with a hub 5 from which extends equi-spaced arms 6, preferably three in number, which arms are arranged at approximately an angle of 45° to the axis of the spindle. As the result of this arrangement, it will be seen that as the barrier is rotated the arms are successively caused to extend in a 50 horizontal plane across the passage when in

barrier position and to extend downwardly when out of barrier position.

This downward direction of the inoperative barrier arms results in the turnstile occupying 5 less space and enables the turnstiles to be positioned closer together when arranged in gangs.

As stated a further object of my invention is to provide means to ensure that the rotating barrier completes its movement as each person passes the turnstile. I therefore provide the following mechanism for this purpose. On the upper side of the hub 5 are a plurality of pins or projections 7, one for each barrier arm 6, and preferably formed as rollers.

On an extension 8 of the bracket 8 is slidably 15 mounted in guides 10 a member 11, which is normally held in the path of the projections 7 by a coil spring 12, one end of which engages a bent pin 13 on the end of the member 11 and its other end is connected to the bracket 8. This member 20 11 is cut away or bevelled off as shown at its rear corner, having reference to the direction of rotation of the barrier, for a purpose which will hereinafter appear.

Pivoted intermediate its ends on the member 11 25 is a lever 14, and the member 11 is provided with a shoulder or abutment 16 at one side of the lever pivot which limits the rocking of the lever in one direction, while the member 11 at the other side of said pivot is shaped or cut away to permit the 30 lever to rock in the opposite direction. A spring 15 tends to hold the lever in engagement with the shoulder 16, and in this position it will be seen that the forward edge of the member 11 and the forward side of the lever are in alignment. The 35 connection between the spring 15 and the lever 14 is of special construction, the lever being provided with a headed pin which is adapted to slide longitudinally in a long loop 15a formed at the end of said spring.

The movement of the member 11 under the action 40 of the spring 12 into the path of the rollers 7 is limited by the engagement of the bent pin 12 with the edge of the bracket extension 8, and thus said member 11 is properly positioned to co- 45 operate with the rollers 7.

This part of the apparatus acts as follows: As the hub 5 is rotated one of the rollers 7 engages the end of the member 11 and pushes the latter out of its path, thus putting the spring 12 under 50 greater tension, but decreasing the tension on the spring 15 until the tension on the latter is relieved altogether and the pin 2 moves along the loop 15a. The roller 7 travels along the end of the member 11 and also along the lever 14 and 55

after the roller 7 passes the pivot point of the lever 14, the latter is gradually rocked as indicated in dotted lines, this being possible due to the pin 2 being away from the end of the loop 15^a of the spring 15, the rocking, however, being controlled by the inclined part of the end of the member 11 with which the lever 14 is adapted to be alined when rocked. As the hub continues its travel, the roller 7 commences to move away from the member 11, whereupon the spring 12, which is stronger than the spring 15 comes into action to return the member 11 to normal position and thus again put the spring 15 under tension. As the hub travels on, the roller 7 then commences to move away from the lever 14, but the latter under the influence of the spring 15 tends to keep the hub moving until the following barrier arm is in centered position.

To prevent the rotating barrier from reverse movement, a dog 4 is pivoted on the bracket 8, which dog is adapted to be pushed out of the way by the rollers 7 and is adapted under its own weight to fall in behind the rollers after they have passed and prevent movement of the rotating barrier in the reverse direction. If desired spring means might be provided to ensure the dog returning to locking position. A stop 17 is provided to limit the movement of the dog out of locking position.

It is also desirable to prevent spinning of the revolving barrier, and I therefore provide the following mechanism for definitely stopping the barrier as each arm reaches the barrier position. Pivotally connected with the ends of a pivoted lever 18 is a stop member 19 and a cam member 20 slidable through holes in the bracket 8 in the path of the rollers 7. A spring 21 normally tends to hold the lever 18 with the cam member 20 in operative position. The operation of this part of the mechanism is as follows. As one roller 7 leaves the lever 14, the preceding roller 7 engages the inclined end of the cam member 20, forcing the latter out of the path of said roller, and thus through the lever 18 moving the stop 19 into the path of the first mentioned roller 7. The rotating barrier, which due to the action of the spring 15 on the lever 14, is travelling at a fairly rapid rate and the roller 7 engages the stop 19 just as the arm reaches central barrier position and the movement of the barrier is definitely checked, the dog 4 at this time being positioned behind the following roller and thus preventing rebound.

The cam member 20 also serves to prevent rebound, as instantly after the barrier is stopped the lever 18 is rocked by its control spring 21 to advance the cam member 20 and retract the stop 19, and thus the barrier is in condition for turning by the following person.

It will be apparent, of course, that the various parts of the mechanism above described co-operate to achieve the desired result. The centering mechanism ensures that the rotary barrier will have sufficient momentum to move it so that the following arm reaches central or barrier position, where the stop 19 stops the movement of the barrier and the dog 4 prevents rebound, but after being stopped the barrier is immediately free for its next movement.

From the construction described it will be seen that I have devised a turnstile which will satisfactorily attain the objects of my invention as set out in the preamble of the specification.

What I claim as my invention is:

1. In a turnstile, the combination of a support; 75 an armed barrier rotatably mounted thereon, and

provided with engaging rollers corresponding in number and spacing with the arms of the barrier; a member slidable on said support; spring means tending to hold said member with one end in the path of said rollers; a lever pivoted on said member and projecting beyond one side of said slide; and spring means normally tending to rock the projecting end of said lever into the path of said rollers.

2. In a turnstile, the combination of a support; an armed barrier rotatably mounted thereon, and provided with engaging rollers corresponding in number and spacing with the arms of the barrier; the axis of said barrier being arranged at approximately 45° to the vertical and the arms on said barriers being arranged at approximately 45° to the said axis; a member slidably on said support; spring means tending to hold said member with one end in the path of said rollers; a lever pivoted on said member and projecting beyond one side of said slide; and spring means normally tending to rock the projecting end of said lever into the path of said rollers.

3. In a turnstile, the combination of a support; an armed barrier rotatably mounted thereon, and provided with engaging rollers corresponding in number and spacing with the arms of the barrier; and means for positively stopping movement of the barrier as each arm reaches barrier position comprising a pivoted lever, a cam member pivotally connected with one end of the lever; spring means normally tending to hold said lever with the cam member in the path of said rollers; and a stop member pivotally connected with the other end of said lever and adapted to be moved into the path of one of said rollers as the cam member is moved out of said path by another roller.

4. In a turnstile, the combination of a support; an armed barrier rotatably mounted thereon and provided with engaging rollers corresponding in number and spacing with the arms of the barrier; a member slidable on said support; spring means tending to hold said member with one end in the path of said rollers; said end having the portion of its end with which the rollers first engage arranged at right angles to its direction of movement and the remainder of its end inclined at an angle to said first mentioned portion; a lever pivoted on said member and projecting beyond one side of said slide; and spring means normally tending to rock the projecting end of said lever into the path of said rollers.

5. In a turnstile, the combination of a support; an armed barrier rotatably mounted thereon, and provided with engaging rollers corresponding in number and spacing with the arms of the barrier; a member slidable on said support; spring means tending to hold said member with one end in the path of said rollers; a lever pivoted on said member, and projecting beyond one side of said slide; and spring means normally tending to rock the projecting end of said lever into the path of said rollers; said first mentioned spring means having greater strength than the last mentioned spring means.

6. In a turnstile, the combination of a support; an armed barrier rotatably mounted thereon, and provided with engaging rollers corresponding in number and spacing with the arms of the barrier; a member slidable on said support; spring means tending to hold said member with one end in the path of said rollers; a lever pivoted on said member and projecting beyond one side of said slide; and spring means normally tending to rock the projecting end of said lever into the path of said

rollers, said last mentioned spring means and lever being connected by a pin and slot connection; said first mentioned spring means having greater strength than the last mentioned spring means.

5. 7. In a turnstile, the combination of a support; an armed barrier rotatably mounted thereon, and provided with engaging rollers corresponding in number and spacing with the arms of the barrier; a member slideable on said support; spring means 10 tending to hold said member with one end in the path of said rollers; a lever pivoted on said member, and projecting beyond one side of said slide; and spring means normally tending to rock the 15 projecting end of said lever into the path of said rollers, said first mentioned spring means having greater strength than the last mentioned spring means, said last mentioned spring means and lever being connected by a pin and slot connection.

20. 8. In a turnstile, the combination of a support; an armed barrier rotatably mounted thereon and

provided with shoulders corresponding in number and spacing with the arms of the barrier; and means for positively stopping movement of the barrier as each arm reaches barrier position, comprising a lever pivoted intermediate its ends on 5 said support; a cam member slideable through the support in a direction parallel to the axis of the barrier and pivotally connected with one end of the lever; spring means normally tending to hold said lever with the cam member in the path of 10 said shoulders; and a stop also slideable through the support in a direction parallel to the axis of the barrier and pivotally connected with the other end of said lever and adapted to be moved into the path of said shoulders as the cam is 15 moved out of said path by another shoulder; and a dog normally occupying a position in the path of said shoulders to prevent backward movement of the barrier, but adapted to be moved out of 20 said position by said shoulders during their forward movement.

HERBERT B. ODELL.
